US0D1107885S

(12) United States Design Patent (10) Patent No.: US D1,107,885 S
(45) Date of Patent: * Dec. 30, 2025

(54) CEILING FAN

(71) Applicant: Hunter Fan Company, Memphis, TN (US)

(72) Inventors: Justin L. Benacquisto, New Baltimore, MI (US); Anthony M. De Leo, Portage, MI (US)

(73) Assignee: Hunter Fan Company, Memphis, TN (US)

() Term: 15 Years

(21) Appl. No.: 29/979,407

(22) Filed: Dec. 18, 2024

Related U.S. Application Data

(63) Continuation of application No. 29/855,231, filed on Sep. 30, 2022, now Pat. No. Des. 1,065,490.

(57) CLAIM

The ornamental design for a ceiling fan as shown and described.

DESCRIPTION

FIG. 1 is a top perspective view of a ceiling fan, showing our new design.

FIG. 2 is a bottom perspective view.

FIG. 3 is a top view.

FIG. 4 is a bottom view.

FIG. 5 is a front view.

FIG. 6 is a rear view.

FIG. 7 is a right-side view; and,

FIG. 8 is a left-side view.

Portions of the ceiling fan shown in broken lines form no part of the claimed design. Jagged broken lines on the ceiling fan illustrate a symbolic break in length and form no part of the claimed design.

1 Claim, 8 Drawing Sheets
